S. L. JEFFERIES

COOLER

Filed March 31 1926

Inventor

S. L. Jefferies

By Geo. P. Kimmel.
Attorney

UNITED STATES PATENT OFFICE.

SAMUEL LIONEL JEFFERIES, OF GAFFNEY, SOUTH CAROLINA.

COOLER.

Application filed March 31, 1926. Serial No. 98,925.

This invention relates to a sectional water cooler, and has for its object to provide, in a manner as hereinafter set forth, a cooler including water, ice and food or produce chambers and constructed in a manner whereby the ice consumption for a predetermined period is materially reduced under such conditions providing for a saving in expense of maintenance; further providing for the convenient storing therein and removing therefrom ice when occasion requires, and further whereby the ice is stored above and separate from the water chamber of the cooler, under such conditions providing for sanitation when the ice is handled, as the handling of the latter, is had without polluting in any manner, the water within the water chamber of the cooler.

A further object of the invention is to provide, in a manner as hereinafter set forth, a water cooler standardized for use in one or more sections and forming a cooling chamber when the sections are used in combination.

Further objects of the invention are to provide, in a manner as hereinafter set forth, a cooler, which is simple in its construction, strong, durable, sanitary, thoroughly efficient in its use, readily assembled, and comparatively inexpensive to manufacture.

With the foregoing and other objects in view, the invention consists of the novel construction, combination and arrangement of parts as hereinafter more specifically described, and illustrated in the accompanying drawings wherein is shown preferred embodiments of the invention, but it is to be understood that changes, variations and modifications can be resorted to which fall within the scope of the claims hereunto appended.

In the drawings wherein like reference characters denote corresponding parts throughout the several views:

Figure 1 is a vertical sectional view of a sectional water cooler.

Figure 2 is a vertical sectional view of a modified form of intermediate section providing the ice chamber.

Figure 3 is a top plan view of the cooler section shown in Figure 2.

Referring to the drawings, the cooler is shown in Figure 1 as consisting of three superposed sections 128', 129' and 139' and each of said sections is formed from an inner and an outer shell. The inner shells of the sections 128', 129' are indicated at 22 and

the outer shells at 21. The inner shells 22 are of greater length than the outer shells 21 and depend below the lower ends of these latter. The shells which form the section 130' are indicated at 21' for the outer shell and 22' for the inner shell and the outer shell 21' is of greater length and depends below the lower end of the inner shell 22'.

Formed integral with the lower end of the inner shell 22 of the section 128' is an imperforate bottom plate 131', which in connection with the inner shell 22 provides the section 128' with a food or produce storage or cooling chamber 134'. Formed integral with the lower end of the inner shell 22 of the section 129' is a perforated bottom plate 26 which in connection with the inner shell 22 of such section provides an ice storage chamber 135'.

The inner shell 22' of the section 130' has formed integral with the lower end thereof a concave bottom member 133, which in connection with the shell 22' forms the section 139' with a water storage chamber 136'. The shell 21' of the section 130' is extended below the bottom member 133 and flared outwardly as at 7 to provide a support for said section 130'.

The shells of each of said sections are spaced from each other and interposed between the shells of each section is a packing means 23. The packing means 23 which is employed in connection with the section 130' is extended throughout the lower face of the bottom member 133, as indicated at 147.

The lower end of each shell 21 is connected to its associated shell 22, above the lower end of the latter, by a coupling piece 24 and which constitutes a closure for the lower end of the space in which is arranged the packing 23 forming a part of a section 128' or 129'. The upper end of a shell 21 is connected to the upper end of its associated shell 22 by a flat coupling piece 25 which forms a closure for the upper end of the space in which is arranged the packing 23. The upper end of the shell 21' is connected to the upper end of its associated shell 22' by a flat coupling piece indicated at 25 and which forms a closure for the upper end of the space in which is arranged the packing 23 for the section 130'.

The outer diameter of the shell 22 of a section 128', is such with respect to the inner diameter of the shell 22 of the section 129', that the outer face of the depending portion of the shell 22 of the section 128' will snugly

engage the upper portion of the inner face of the shell 22 of the section 129'. The outer diameter of the shell 22 of the section 129', is such with respect to the inner diameter of the shell 22' of the section 130' that the outer face of the depending portion of the shell 22 of the section 129' will snugly engage the upper portion of the inner face of the shell 22' of the section 130'. The interengagement of one of the shells 22 with the other shell 22 and one shell 22 with a shell 22' will set up a frictional lock between the sections when they are set up in superposed position.

When the sections 128' and 129' are mounted in superposed relation, the coupling pieces 24 are seated upon the coupling pieces 25. The outer diameter of the shells 21 and 21' are the same so that when the sections 128' and 129' are mounted in superposed relation with the section 130', the outer face of said sections 128' and 129' will be flush with the outer face of the section 130'.

To facilitate the positioning of the sections 128' and 129' relative to the section 130', or for removing of said sections 128' and 129' from the section 130', the sections 128', 129' and 130' are provided with a pair of handle members 28.

An interengaging and overlapping cover 37 is provided for the upper section of the cooler, and said cover 37 is common to any one of the cooler sections.

Referring to Fig. 3 which represents an ice chamber with a removable perforated bottom and which represents a modified form of the ice chamber. The shells 21^a and 22^b, the coupling pieces 24 and 25 and the packing 23 between the shells are of the same construction as section 129', Fig. 1. The two handle bars 28 also are of the same construction. The point of difference in construction is whereby the shell 22^b depends below the shell 21^a, and at the lower extremity the shell 22^b flares inward an appropriate distance in an angular manner to form a circular rest 12 and leaving a circular opening, this opening to be covered by a circular, perforated, removable bottom or plate 12', and said plate fitting cojointly between the inner shell 22 to form the ice chamber 135''. The inward angular, flaring rest 12 on the lower extremity of the inner shell 22^b serving as a support for the removable, perforated bottom 12'. The perforated, removable bottom 12' serves to promote sanitation of the middle section of the cooler and thereby renders this section more easily cleaned and sterilized.

Referring to figure 3 which is a preferable design of the removable bottom or plate 12', and which is made to fit cojointly between the inner shell 22^b, Fig. 2, and to be supported by the rest 12, Fig. 4. The periphery of the plate 12' may be reinforced and is circular in form. The plate 12' is formed pro-

portionately distanced three circular rows of perforations 20' symmetrically or otherwise arranged to serve as an escape for the water from the ice in the chamber 135'', Fig. 2. The perforations may be made of any shape or form to best serve the purpose.

As will be seen the ice can be handled independent of polluting the water, that the convenient storing and removal of the ice can be had, and that produce or food can be sorted and removed without coming in direct contact with the ice.

While the preferable form and shape of the above described water cooler and refrigerator is circular or round in the construction of the different sections and bottoms, but at the same time it is borne in mind that the different parts may be constructed square, or hexagonal or in any modifications of these shapes.

It is thought that the many advantages of a water cooler, in accordance with this invention can be readily understood, and although the preferred embodiments of the invention are as illustrated and described, yet it is to be understood that changes of details of construction can be had which will fall within the scope of the invention as claimed.

What I claim is:—

A cooler comprising a body portion formed of a plurality of superposed removable interengaging sections each formed of concentrically arranged spaced inner and outer shells having a packing means interposed therebetween said outer shells having the outer peripheries thereof flush with each other, each of said sections having a horizontally disposed coupling piece connecting the upper ends of the shells therof together, each coupling piece secured to and flush with the top edges of a pair of shells, each upper section having its inner shell extending below its outer shell and further including a horizontally disposed coupling piece connecting the lower end of the outer shell to the inner shell above the bottom of the latter, seating directly upon the top coupling piece of a lower section and flush with the bottom edge of the outer shell of an upper section, the lowermost one of said sections having its outer shell extending below its inner shell to provide a support, each of said sections further including a bottom integral with the lower end of the inner shell thereof, the depending portion of the inner shells of the upper of said sections frictionally engaging directly with the inner faces of the inner shells of the lower sections for detachably connecting the sections together in superposed relation, and a cover element common to any one of said sections.

In testimony whereof, I affix my signature hereto.

SAMUEL LIONEL JEFFERIES.
